United States Patent Office

Des. 178,200
Patented July 3, 1956

178,200

CANDLE OR THE LIKE

Edward J. McKenzie and Andrew A. Nowak, Jr.,
New York, N. Y.

Application February 18, 1955, Serial No. 34,566

Term of patent 14 years

(Cl. D73—1)

The figure on the drawing is a perspective view of a candle showing our new design; the opposite two sides being substantially similar in appearance to the two sides shown.

We claim:

The ornamental design for a candle or the like, as shown and described.
